(57) **CLAIM**

The ornamental design for a V-hand shaped display, as shown and described.

DESCRIPTION

FIG. 1 is a front view of a V-hand shaped display showing the claimed design;

FIG. 2 is a rear view thereof;

FIG. 3 is a right side view thereof;

FIG. 4 is a left side view thereof;

FIG. 5 is a bottom view thereof;

FIG. 6 is a top view thereof;

FIG. 7 is a front view thereof shown in an environment in which the claimed design may be used; the words “LOGOS HERE” indicate where a user might place an ad; and,

FIG. 8 is a rear view thereof.

The bottom is in part plain and unornamented, and the unornamented portion is not claimed as part of the design.

The broken lines of the words “LOGOS HERE” in FIGS. 7 and 8 form no part of the claimed design where they appear as an indicator. The broken lines of the bottom of FIG. 5 form no part of the claimed design.

The present design is for a V-hand shaped display used for displaying various things, such as team names and/or logos, and is commonly worn over a person’s hand.
